UNITED STATES PATENT OFFICE.

WILLIAM A. JOHNSON, OF TORONTO, ONTARIO, CANADA.

ELECTRIC-LIGHT-CIRCUIT CUT-OFF SWITCH.

SPECIFICATION forming part of Letters Patent No. 390,481, dated October 2, 1883.

Application filed November 25, 1887. Serial No. 236,090. (No model.)

To all whom it may concern:

Be it known that I, WILLIAM ASAHEL JOHNSON, of the city of Toronto, in the county of York, in the Province of Ontario, Canada, 5 manufacturer, have invented a certain new and useful Improvement in Electric-Light-Circuit Cut-Off Switches, of which the following is a specification.

The object of the invention is to design a 10 simply-constructed electric-light-circuit cut-off switch by which the current may be completely cut off from the loop-circuit; and it consists, essentially, of two metal levers coupled together by an insulated connection and pivoted upon the binding-posts of the dynamo-circuit, the said levers being arranged in connection with the contact-plates connected, respectively, with the binding-posts in the loop-circuit and with one of the binding-posts in 15 the dynamo circuit in such a manner that the current may be thrown on and off the loop-circuit by the simple adjustment of the levers in such a manner that the levers will make contact with the binding-posts of one circuit 20 before breaking contact with the others, all as more fully hereinafter described and claimed.

Figure 1 represents a view of my improved switch set so that the loop-circuit is completely cut off. Fig. 2 shows the switch set 25 so that the current shall pass through the loop-circuit.

A and B represent the binding-posts of the dynamo-circuit, and C D the binding-posts of the loop circuit. The lever E is pivoted upon 30 and is in contact with the binding-post A, and the lever F is pivoted upon and in contact with the binding post B. These two levers E and F are coupled together by the insulated link G, so that the movement of one lever shall 35 be communicated to the other.

H is a contact-plate connected to the binding-post C, and extending toward the lever E, as shown. I is a similar contact-plate connected to the binding-post D and extending 40 toward the lever F. J is also a contact-plate connected to the post A and extending past the post C toward the lever F, as indicated.

When my switch is set as shown in Fig. 1, the current will pass from the binding-post B 45 along the lever F, and then through the contact-plate J, through the binding-post A, and back

to the dynamo, and as both binding-posts C and D are completely isolated no current can possibly reach the loop-circuit. When the switch is set as shown in Fig. 2, the current 55 from the dynamo enters the binding-post B, along the contact-plates F and I, and thence into the loop-circuit through the binding-post D, and back again to the dynamo, through the binding-post C, contact-plate H, lever E, and 60 binding-post A.

It will be noticed that the distance between the contact-plates I and J is less than the width of the lever F. Consequently the said lever F comes in contact with one of the said 65 plates before it loses contact with the other.

It will be seen that by employing a cut-off switch such as the one described a loop-circuit running into a building may be completely cut off from the main circuit, leaving 70 the wires and lamps within the building perfectly safe to handle, and that the switch makes contact with the plates H and I before breaking contact with the plate J, and vice versa, so that there will be no spark and no 75 danger from fire. This is important.

What I claim as my invention is—

1. The combination, with the binding-posts A B C D, of two levers pivoted upon the binding-posts A B, and connected to move together, the contact-plates H I, connected to the binding-posts C D, respectively, and the inclined contact-plate J, connected with the binding-post A and extended between the plates H I, substantially as and for the purpose specified.

2. The combination, with the binding-posts A B C D, of two levers pivoted upon the binding-posts A B and connected to move together, the contact-plates H I, connected to the binding-posts C D, respectively, and the inclined contact-plate J, connected with the binding-post A and extended between the plates H I, the space between the plates I J being less than the width of the lever F, substantially as and for the purpose specified.

Toronto, October 28, 1887.

WILLIAM A. JOHNSON.

In presence of—

CHARLES C. BALDWIN,
DONALD C. RIDOUT.
